UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

BUTTON-SEWING MACHINE.

Application filed February 28, 1924, Serial No. 695,660. Renewed November 20, 1924.

To all whom it may concern:

Be it known that I, ROBERT L. LYONS, a citizen of the United States, residing at Waltham, in the county of Middlesex and State of Massachusetts, have invented new and useful Improvements in Button-Sewing Machines, of which the following is a specification.

This invention relates to machines for sewing on buttons and is more particularly concerned with the means for holding shank or one hole buttons in proper relation to the sewing instrumentalities. By "shank or one hole button" is meant one which has its attaching stitches passed through its back portion which may be perforated for the purpose, or may be of material such as cloth through which the needle may make its own hole.

This invention, therefore, provides a construction whereby the button clamp is designed to engage the edges of the button to present the face of the button approximately parallel to the path of the needle during its sewing strokes and close to the work plate. While not restricted to such use this clamp is designed more particularly for use with a single thread machine in which the thread is knotted at the last stroke of the machine. At the completion of the sewing operation the clamp may be raised from the work table by the operator to raise the work and break the stitching thread and on a further upward motion of the clamp beyond a predetermined point, the upper jaw is given a more rapid movement than the lower to separate the jaws and release the button.

Another feature of the invention resides in means for urging the button clamp against the work plate.

For a more complete understanding of this invention reference may be had to the accompanying drawings in which—

Figure 1 is a fragmentary side elevation of a button sewing machine employing the button clamp of this invention.

Figure 2 is front elevation thereof.

Figure 3 is a vertical section on line 3—3 of Figure 1.

Figure 4 is a perspective of the clamp.

Figure 5 represents perspectives at right angles to each other of a shank button.

Figures 6 and 7 are side elevations of other forms of one hole buttons.

The subject matter of this invention is

shown as applied to a button sewing machine of well known construction having a forwardly extending work table 1 having a work plate 2 on its forward upper face. Above the work table is a housing 3 carried at the forward end of a hollow frame arm 4, the housing 3 enclosing a portion of the needle mechanism, the needle bar being indicated at 5. This needle bar is permitted a lateral as well as a vertical motion so that at alternate strokes it may pass through the shank of the button and the work as will later be described. The frame arm 4 merges at its rear end with a frame post 6 extending upwardly from the work table 1 and adjacent thereto is pivoted at 7 the rear end of an arm 8. This arm extends forwardly beneath the frame arm 4 and at its forward end it has fixed thereto with capability of longitudinal adjustment a supporting plate 9 of the clamping mechanism. This longitudinal adjustment may be effected by means of bolts 10 threaded in openings 11 in the support 9, and passing through slots extending longitudinally through the arm 8. This support 9 is formed as a plate and to the forward edge thereof is fixed a depending member 12. This member, as shown, is fixed to the support 9 by bolts 13 passing through slots arranged laterally in the support 9, these bolts being threaded into the member 12.

By these two adjustments the member 12 may be given an adjustment longitudinally and laterally relative to the arm 8. At the lower end of the member 12 is a forwardly extending base 14 which forms a lower button clamping jaw.

The lower surface of this member 14 is formed to rest on the work plate 2 and in its upper face is formed a depression 15 shaped to receive the edge of a button of the type shown, for example, in Figure 5 at 16, Figure 6 at 160 or Figure 7 at 165. Communicating with this depression 15 is a lateral slot 17 extending inwardly to a sufficient distance to align with the button hole 18 which extends transversely of the button 16 and through the shank portion 19 thereof when the button is in position, or with the button hole 161 of the button 160, or forwardly of the rear end of the cloth shank of button 165. Pivoted to one face of the member 12 is a lever 20, the pivot as shown being formed by means of a bolt 21 passing therethrough

and threaded into the member 12. This lever 20 has its forward end downwardly and inwardly turned as at 22 to form the upper button-engaging jaw of the clamp. 5 Its lower face is formed with a depression 23 to engage the edge of the button and a slot 24 is formed through its edge similar to the slot 17 of the lower clamping member. At the rear end of the lever 20 back of the pivot bolt 21 a notch 23 is formed therein over which may engage the lower end of a spring 25, the opposite end of which is made fast 10 as at 26 to the arm 8. This spring acts to urge the upper clamping jaw 22 toward the lower clamping jaw 14 to engage a button therebetween on edge in substantially parallel relation to the sewing path of the needle N carried by the needle bar 5.

The button clamp is normally held down 20 against the work plate 2 and for this purpose mechanism shown more clearly in Figure 3 has been provided. This comprises a sleeve 30 fixed to the upper wall of the frame arm 4 and telescoping within this sleeve is 25 the upper end of a tube 31. The lower end of this tube is closed off by means of a plug 32 and is positioned to impinge on the outer end of the arm 8. Threaded through the upper end of the sleeve 30 is an adjusting bolt 33 which preferably is provided with a lock nut 34, this adjusting bolt extending within the upper end of the tube 31. Within the tube 31 and bearing at opposite ends on the lower end of the bolt 33 and the upper end of the plug 32 is a coil spring 35. This spring acts to force the tube downwardly and therefore to yieldingly press the outer end of the arm 8 toward the work plate, and its tension may be adjusted by manipulation 40 of the bolt 33.

Means are also provided of any suitable type for raising the clamp from the work so as to raise the work and break the thread. Such means are old and well known, a portion 45 thereof being shown in the drawings comprising an ear 36 made fast to the outer end of the arm 8 to which is attached a lifting chain 37. Commonly this lifting chain is actuated through a suitable connection to 50 a treadle.

Provision is made by which after a predetermined extent of movement of the clamp away from the work table sufficient to ensure the breaking of the thread, the button is 55 released. As shown this comprises an abutment bar 40 adjustably connected rigidly to the frame arm 4. As shown this connection comprises a screw 41 threaded in the side portion of the frame arm 4 and passing 60 through a slot 42 in the upper end of the bar 40. This bar may be adjusted angularly about the screw 41 or longitudinally thereon as may be desired so that its lower end may be struck by the lever 20 after a predetermined extent of raising of the clamp. The

impingement of this lever thereon is back of the pivot bolt 21 so that as the clamp is raised further after such impingement has taken place, the rear end of the lever is rocked downwardly relative to the lower 70 clamping jaw so that the outer end of this lever, comprising the upper clamping jaw is moved upwardly at a faster rate than the lower clamping jaw, thus separating the jaws and releasing the button. When the 75 clamp is allowed to descend, the spring 25 returns the upper jaw to its former position in clamping engagement with a button placed between the jaws as shown best in Figure 2. The perforation 18 through the 80 button is positioned vertically so that the needle N may pass through this perforation and through the folded edge of the work shown at W in Figure 2 which is presented adjacent thereto, the needle being moved laterally relatively to the work and button to cause alternate sewing strokes to be made through the work and through the button perforation.

On a single thread machine of the type 90 shown, the last two strokes of the needle are caused to take place in the same lateral position, this, in a manner well understood in the art, causing the thread to be knotted. The subsequent raising of the button clamp, 95 as hereinbefore described, causes the work and the button to be first raised from the work table and the thread to be broken and the button is then released by the opening of the clamping jaws.

Having thus described an embodiment of this invention it should be evident that many changes and modifications might be made therein without departing from its spirit or scope as defined by the appended claims. 105

I claim:

1. In a machine of the class described, a work plate, a button clamp movable toward and from said plate, said button clamp comprising a lower jaw having a recess to receive the edge of a one hole button, a lever pivoted to said lower jaw, the outer end of said lever being formed as an upper jaw cooperating with said lower jaw to clamp the button therebetween, and a fixed abutment 110 against which said lever impinges on the inner side of its pivot as said clamp is moved away from said work plate to a predetermined extent, to release the button on further movement of said clamp in the same direction.

2. In a machine of the class described, a work plate, a pivoted arm, a button clamp fixed to said arm and movable by the swinging of said arm about its pivot toward and from said work plate, said clamp comprising a support fixed to said arm and longitudinally adjustable relative thereto, a lower button clamping jaw fixed to said support and adjustable laterally thereof, said jaw being 115 120

5 formed to engage the edge of a button, a lever pivoted to said lower jaw and having its outer end formed as an upper clamping jaw, a spring engaging the opposite end of 10 said lever and said arm to press said upper jaw toward said lower jaw, and an adjustable fixed abutment with which said lever engages when said clamp is moved to a predetermined distance from said work plate to 15 cause said lever to swing on further movement of said clamp in the same direction in opposition to said spring.

3. In a machine of the class described, a work plate, a pivoted arm, a button clamp 15 fixed to said arm and movable by the swinging of said arm about its pivot toward and from said work plate, means to press said clamp toward said work plate, means to move said clamp from said work plate in op- 20 position to said pressing means, said clamp comprising a support fixed to said arm and longitudinally adjustable relative thereto, a lower button clamping jaw fixed to said sup- 25 port and adjustable laterally thereof, said jaw being formed to engage the edge of a button, a lever pivoted to said lower jaw and

having its outer end formed as an upper clamping jaw, a spring engaging the opposite end of said lever and said arm to urge 30 said upper jaw toward said lower jaw, and an adjustable fixed abutment with which said lever engages when said clamp is moved to a predetermined distance from said work plate to cause said lever to swing on further movement of said clamp in the same direction in 35 opposition to said spring.

4. In a machine of the class described, a work plate, a pivoted arm, a button clamp carried by said arm to move toward and from said work plate on the swinging of 40 said arm, means for yieldingly pressing said clamp toward said plate comprising a sleeve, a tube telescopically arranged within said sleeve, one end of said tube being closed and bearing on said arm, a screw threaded in said 45 sleeve and extending within the opposite end of said tube, and a coil spring within said tube and bearing between the inner end of said screw and the closed end of said tube.

In testimony whereof I have affixed my signature.

ROBERT L. LYONS.
